His Attorney

UNITED STATES PATENT OFFICE.

THOMAS STYAN, OF MAYS LANDING, NEW JERSEY, ASSIGNEE TO LOUIS ELY, OF VINELAND, NEW JERSEY.

GRIP.

Application filed March 6, 1924. Serial No. 897,417.

To all whom it may concern:

Be it known that I, THOMAS STYAN, a citizen of the United States, residing at Mays Landing, in the county of Atlantic and State of New Jersey, have invented certain new and useful Improvements in Grips; and I do hereby declare the following to be a full, clear, and exact description of the invention, such as will enable others skilled in the art to which it appertains to make and use the same.

This invention relates to improvements in grips for handles, such as the levers of automobile gear shifts and the handle bars of bicycles, and elsewhere where a firm hold is desirable.

Among the objects in view is the provision of a structure which, while affording an easy, firm hold and capacity for prolonged usage, also possesses attractiveness of appearance and properties enabling ready visual observance in reduced light.

A more detail object is the provision of effective means of connection of the grip to the handle or lever in a manner insuring against injury to the grip, and a still further object is the adaptation of such connecting means to handles or levers of variable dimensions.

With these and further objects in view as will in part hereinafter become apparent and in part be stated, the invention comprises certain novel constructions, combinations and arrangements of parts as subsequently specified and claimed.

In the accompanying drawings,—

Figure 1 is a vertical, central section through a structure embodying the features of the present invention, and showing the same applied.

Figure 2 is a view in side elevation of the threaded sleeve detached.

Figure 3 is a view similar to Figure 1 with the grip shown applied to a lever having a threaded receiving end of greater diameter than that seen in Figure 1 and with the adapter consequently omitted.

Figure 4 is a vertical, central section through the sleeve adapter engaged by a bolt adapter which in turn engages a modified form of lever.

Figure 5 is a view similar to Figure 4 of the same parts with the sleeve adapter indicated as abbreviated to enable a portion

of the lever to enter the threaded sleeve of the grip.

Figure 6 is a sectional elevation of a further slight modification of the grip shown applied, and for purposes of interpretation of the appended claims this embodiment may be considered preferred.

Referring to the drawings by numerals, 1 indicates a globular body formed of opal glass and colored in imitation of onyx or other stone, but possessing sufficient translucence to give the appearance of light, and, accordingly, facilitate observance when sought by the hand of the operator in reduced light. The body 1 is formed by being cast from molten glass, and in the operation of casting the body is formed with a depression or recess 2, which is circular in cross section at all points and tapers inwardly to its base. The recess 2 is formed at its base or inner end with a parti-globular projection or lug 3 arranged centrally.

Anchored in the recess 2 is a threaded sleeve 4 tapered to correspond with the taper of the recess 2 and roughened on its exterior, as by being provided with knurling for enhancing the bonding action of cement. The diameter of the sleeve 4 is slightly less than the diameter of recess 2, and the intervening space is filled with cement, shown at 5, which effectively anchors the threaded sleeve 4 within the socket. The lug or projection 3 is proportioned to sufficiently nearly fit within the inner end of the sleeve 4 to center the sleeve within the recess 2 when the sleeve is first introduced, so as to insure a substantially equal thickness of cement coating 5 at all places about the sleeve 4. The sleeve 4 is threaded internally for receiving the handle or lever to which the grip or body 1 is to be attached, and the inner extremity of the sleeve 4 is left smooth, as indicated at 6. That is to say, the threads terminate short of the inner end so that when the sleeve 4 is threaded onto a lever or an adapter engaging the lever said lever or adapter cannot enter the sleeve beyond the outer extremity of the smooth portion 6. To avoid the possibility of the threading of the sleeve 4 onto a threaded portion of a lever having itself a smooth extension capable of projecting along the smooth portion 6 and engaging the body 1 itself, a cushion 7 is provided at the inner

end of the sleeve 4 and formed of cork or other appropriate material, which will serve to allow end contact of the engaged lever or adapter with sufficient force to enable 5 a firm seating of the sleeve 4 on such lever or adapter without danger of injury to the body 1 through the end thrust of such lever or adapter.

As seen in Figure 1, a lever 8 is engaged, 10 the said lever 8 being formed with a threaded portion 9, which is threaded into an adapting sleeve 10, which adapter or adapting sleeve is in turn threaded into the threaded sleeve 4. It is to be observed that the 15 adapter or adapting sleeve 10 will always have the external dimension the same and will be threaded to correspond with the internal threads of the sleeve 4, but the bore of the adapter 10 will be varied in diameter and 20 in thread to correspond with the diameter and thread of the threaded portion of the particular lever to be engaged. Thus, the body 1 may be readily applied onto any lever now in use having a threaded portion either 25 dimensioned and proportioned to engage the threads of the sleeve 4, as seen at 11 in Figure 3, or having a threaded portion of less diameter.

However, in the automobile industry some 30 cars are provided with gear shifting levers having threaded sockets at the outer extremity of such levers and to enable the application of the body 1 to such a lever, the arrangement seen in Figures 4 and 6 is employed in which the adapter or adapting sleeve 10 is utilized and is engaged internally by a bolt adapter or externally threaded member 12 designed to project beyond the adapter 10 and enter the threaded socket or 35 recess of the modified lever 13. In Figure 5 is seen a slight modification of the structure shown in Figure 4 in which the adapter 10' is employed, which is identical with adapter 10 except that it is made much shorter, and 40 adapter 10' is engaged by a bolt adapter 12' corresponding with the adapter 12 and in turn engaging the socket of the lever 14. In this particular embodiment, the socketed portion 14 is of a diameter slightly less than 45 the diameter of the adapter 10', so as to be free to enter the sleeve 4 and thereby allow the body 1 to be moved down over and conceal all or a part of the socket 14 by a threading action of the sleeve 4 on the adapter 10'.

55 In actual practice, in the making of grips of this type, I have found that great care must be exercised to prevent a contour or formation of the body 1 such as will place the material under stress and result in cracking and eventual destruction thereof. I have discovered that such cracking occurs occasionally where the recess 2 is cast with its outer terminus bounded by a sharp, circular edge. I have discovered also that the danger 60 of cracking may be largely eliminated by the

formation of a rounded bead or rounded shoulder 15 at the place of meeting of the exterior surface of the globe or body 1 with the interior surface outlining the recess 2. In other words, the recess 2, when caused to 70 meet the exterior surface of the body 1 by the interposition of a rounded shoulder, offers less occasion for stress, and, therefore, frees the structure from the danger of cracking and becoming useless. 75

The utility of the body 1 or grip is inclusive of the functions of the devices named, and also various other articles in other arts where a good, firm hold is required for the pulling or shifting of parts, such as bureau drawers and the like, and in every instance the material affords such opportunity for light reflection as to almost amount to self-illumination and resultant ease of location by the hand of the operator. 80

In lieu of or in addition to the protection afforded by the smooth portion 6 of sleeve 4, the adapter 10 preferably has its outer end portion formed smooth, as indicated at 17, so that the external threads terminate 90 short of the length of the adapter, whereby the adapter cannot enter the sleeve 4 for its full length even though the adapter may be shorter than the threaded portion of the sleeve 4. These smooth portions 6 and 17 are desirable to insure against the threading of a member so far into the sleeve 4 as to exert such an amount of pressure on the cushion 7 as to tend to force the body 1 away from the sleeve 4 and thereby strip or break 95 loose the cement 5.

In Figure 6 is shown a structure identical with that seen in Figure 1, except the fact that the adapters seen in Figure 4 are shown as applied, and the body 1' has its rounded shoulder 15' exaggerated into an annular bead 16, both for increasing the aesthetic appeal and adding to the stability of the vitreous substance around the sleeve receiving recess. The other parts shown in Figure 6 being identical with those above described, the same reference numerals have been applied and the same description is applicable. 105

While the body 1 or 1' has been above described as of glass, it may be formed of any similar appropriate material susceptible of being molded and vitrified, and is always preferably of the substance possessing the luscency desirable for this type of structure. It is also to be understood, of course, that when glass is utilized, it is preferably supplied with coloring matter while molten in a manner to cause the final product to have the grained appearance of onyx or like stone. 110

120 What is claimed is:—

1. A grip of the class described comprising a body of lucent material, and means of anchorage thereof to a part to be moved, the body being formed of the contour of a rounded shoulder approaching the anchor- 125 130

age means to prevent cracking incident to strain about the places of meeting between the body and the anchorage means.

2. A grip of the class described comprising a vitreous body having a recess and a rounded shoulder leading from the exterior surface of the body to the surface of the recess, and means within the recess for connecting the body to a part to be moved.

10 3. A grip of the class described comprising a vitreous body having a recess and a rounded, annular shoulder leading from the exterior surface of the body to the surface of the recess, and means within the recess 15 for connecting the body to a part to be moved.

4. A grip of the class described comprising a vitreous body having a recess, and a rounded, annular shoulder leading from the exterior surface of the body to the surface of the recess, and means within the recess for connecting the body to a part to be moved, the said shoulder being shaped to form an annular bead.

25 5. A grip comprising a vitreous body having a tubular recess and a projection extending outward at the inner end of the recess, and a threaded sleeve cemented within the recess, the projection being proportioned to 30 enter the inner end of the sleeve and center the sleeve relative to the recess.

6. A grip comprising a vitreous body having a tubular recess, and a threaded sleeve

anchored in the recess, means being provided within the sleeve for preventing a threaded member engaging the sleeve from moving within the sleeve for the full length thereof.

7. A grip comprising a vitreous body having a tubular recess, and a threaded sleeve anchored within the recess, the threads of 40 the sleeve terminating short of the length of the sleeve.

8. A grip comprising a vitreous body having a tubular recess, a threaded sleeve anchored therein, and a cushion at the inner 45 end of the sleeve.

9. A grip comprising a vitreous body having a tubular recess, a sleeve anchored in the recess and having internal threads, and a threaded adapter engaging the threads of 50 the sleeve and having a smooth portion for limiting the extent to which the adapter may enter the sleeve.

10. A grip comprising a vitreous body formed with a recess, a sleeve anchored in 55 the recess, an internally and externally threaded tubular adapter engaging the threads of the sleeve, and an externally-threaded adapter engaging the internal threads of the first-mentioned adapter. 60

In testimony whereof I affix my signature in presence of two witnesses.

THOMAS STYAN.
